UNITED STATES PATENT OFFICE.

ANNIE LAURIE JUST, OF SYRACUSE, NEW YORK.

DESIGN FOR A MONUMENT.

40,313.

Specification for Design.

Patented Oct. 12, 1909.

Application filed June 24, 1909. Serial No. 504,175. Term of patent 14 years.

To all whom it may concern:

Be it known that I, ANNIE LAURIE JUST, a citizen of the United States, residing at No. 915 West Genesee street, in the city of Syracuse, county of Onondaga, and State of New York, have invented a new, original, and ornamental Design for Monuments, of which the following is a specification, reference being had to the accompanying drawing, in which I show a front view of the monument.

The salient features of the design consist of the two figures cut in relief upon a column of stone, such as granite or the like, the face

of the column being irregular in form, and the two figures being partially draped; one carrying the Book of Life, and the other supporting the torch to illuminate the pathway, in which is shown the representation of a palm leaf, the whole forming a unitary monument.

I claim—

The ornamental design for a monument, as shown and described.

ANNIE LAURIE JUST.
